TYPOGRAPHICAL SLUG CASTING
MACHINE

Christian Augustus Albrecht, Berlin, Germany,
assignor to Mergenthaler Linotype Company,
Brooklyn, N. Y.

Application February 14, 1934, Serial No. 711,119
In Germany February 17, 1933

45 Claims. (Cl. 199—50)

In matrix composing and line casting machines, in which the composed line is clamped between two vise jaws for presentation to the casting mechanism, it has already been proposed, 5 when casting lines of shorter length than those corresponding to the length of the casting mold slot, to move the vise jaws relatively to one another by a special operating mechanism, so that, according to the adjustments made, the line will 10 be centred or quadded to one side or the other of the cast slug. In arrangements of this kind, it has already been proposed, to subject both jaws to longitudinal displacement and to control them by a vertically movable rod actuated by levers 15 or links. This rod operates through a disc or collar upon studs carried by levers connected to the adjustable jaws, the said disc or collar being provided with gaps which can be positioned, by rotation of the collar, to actuate either or both of 20 the jaws. When both jaws are operated the line will be centred, when either jaw is operated independently the line will be quadded to one side or the other, and when both jaws are disconnected, the device will be inoperative.

25 The object of the present invention is a further development of this arrangement and more especially is productive of a considerable simplification of the operating mechanism of the controls, the connecting and disconnecting means, and the 30 pump operating mechanism connected with the said arrangement. The specific improvements according to the invention are fully set forth in the detailed description to follow, and illustrated 35 in the accompanying drawings:—

In the said drawings, which illustrate by way of example, different constructional forms of the devices according to the invention:—

Figure 1 is a front elevation of the pertinent 40 parts of a machine showing the application thereof to one constructional form of the invention;

Figure 2 is a view similar to Figure 1, showing the devices in an inoperative position;

Figures 3 to 6 are horizontal sections, each 45 taken on the line 3—3 of Figure 2, showing certain of the parts in respectively different positions of adjustment;

Figure 7 is a side elevation of part of the rod 50 represented in section at the left-hand side of Figures 3 to 6;

Figure 8 is a front elevation, partly in section, of a portion of the mechanism shown in Figures 1 and 2, drawn to a larger scale than the said figures;

55 Figure 9 is a side elevation of the upper part

of Figure 8, as seen from the left-hand side of that figure;

Figure 10 is a section taken on the line 10—10 of Figure 9, as viewed in the direction of the arrows of that figure;

Figure 11 is a sectional plan view taken on the line 11—11 of Figure 8;

Figure 12 is a left-hand side elevation of the lower part of Figure 8;

Figure 13 is a vertical section of a portion of Figure 1 on an enlarged scale;

Figure 14 is a plan of the parts shown in Figure 13;

Figure 15 is a vertical section taken on the line 15—15 of Figure 1, as seen in the direction 15 of the arrows;

Figure 16 is a front elevation of supplementary means for facilitating the alternate setting of full lines and lines to be quadded;

Figure 17 is a side elevation of a portion of Figure 16, but drawn to a larger scale;

Figure 18 shows a portion of Figure 16, partly in section and drawn to a larger scale;

Figure 19 is a front elevation of a modified form 25 of the means shown in Figures 16 to 18;

Figure 20 is a plan thereof, partly in section;

Figure 21 shows a portion of Figure 19 with the parts in respectively different positions;

Figure 22 is a front elevation, similar to Figure 1, but partly in section, showing a modified constructional form of certain of the parts;

Figure 23 is a horizontal section taken on the line 23—23 of Figure 22, drawn to a larger scale;

Figures 24, 25 and 26 illustrate, on a still larger scale, various positions of adjustment of the means controlling the inward movement of the jaws;

Figure 27 illustrates, also on an enlarged scale as compared with Figure 1, the jaw-tightening ratchet mechanism and part of the pump stop- 40 ping device controlled thereby;

Figure 28 is an enlarged front elevation, partly in section, of a modified constructional form of the gearing connecting the ratchet mechanism with the rod controlling the movement of the 45 jaws;

Figure 29 is a diagrammatic side elevation of the justifier operating devices, and

Figures 30 and 31 are respectively a front elevation and a vertical section of a special constructional form of the guideway for the clamping jaws.

In the drawings, 1 is the so-called vise frame, which, as customary, is pivotally mounted in the machine frame by studs 1^a, and 2, 3 are the 55

line-clamping jaws which are slidably guided in the vice frame 1. To enable the jaws to be moved for centring a short line, or for quadding a short line either to the right or to the left, and to close the portion of the mold slot not closed by the line itself, these jaws are pivotally connected to levers 6 and 7 respectively by two links 4 and 5. The levers 6, 7, are respectively pivoted on the vise frame by studs 8 and 9. Fast to the respective levers 6, 7, are arms 10 and 11. The arm 11 carries a pin 12 (Figures 3 to 6), and the arm 10 has at its forward end, an aperture through which is adapted to pass a pin 14 carried by one arm of a two-armed lever 13. The lever 13 is also pivoted on the stud 8, but is free to move axially thereon, and its free end is engaged within an inclined slot 15 in a vertical rod 16 (see particularly Figure 7). The raising and lowering of the rod 16 thus moves the lever 13 to and fro along the stud 8, thereby either retracting the pin to the position in which it is shown in Figure 3, or protruding it beyond the face of the lever 10 to the position in which it is shown in Figures 4 to 8.

The two pins 12 and 14 are located in a plane lying between two discs 17 and 18 which are rigidly secured to a vertically movable sleeve 19, which may be turned so as to bring the discs into one or another of the three positions shown in Figures 4 to 6. A segment of the upper disc 17 is cut away so that, according to the angular position of the discs and the position of the pin 14, the pins 12, 14 and levers 10, 11, may be selectively actuated by vertical movement of the sleeve 19. This will be understood by reference to Figures 3 to 6. Figure 3 shows the position in which neither of the pins will be engaged by the disc 17; Figure 4 that in which only the pin 14 will be so engaged; Figure 5 the position in which both pins will be engaged, and Figure 6 the position in which the pin 12 only will be engaged.

The turning of the sleeve 19 is effected by a toothed wheel 20, the hub 21 of which is journaled in a bearing 22 on the vise frame, (see particularly Figure 13). A set screw 23 in said bearing, engages a circumferential groove in the hub 21, so that the wheel 20 is permitted to turn but is held against axial movement. The wheel 20 engages a vertical groove 20^b in the sleeve 19 by a key or feather 20^a, so that the sleeve can move axially relatively to the wheel but must move angularly therewith. The wheel 20 meshes with a rack 24 on a slide 25, which latter carries a second rack 26 (Figures 1 and 2), meshing with a toothed wheel 27. The toothed wheel 27 is rotatable on a stud fast on the vise frame and can be adjusted, by means of a crank handle 28, to three different positions in any one of which it can be locked by a spring plunger 29 engaging an appropriate hole in a fixed segment 30. In Figure 1 the crank handle 28 is shown in its central position appropriate to the position of the disc 17 illustrated in Figure 5, while in Figure 2 the handle is shown adjusted to its topmost position for setting the discs 17 and 18 to the position indicated in Figures 3 and 4. When the handle 28 is in the third position (not shown) in which it is directed downwardly, the disc 17 will be positioned as in Figure 6 so that it can act only upon the stud 12.

The sleeve 19, guided in the bearing 22, encircles a rod 31 relatively to which it is capable of turning. The rod 31 is rigidly connected to, or integral with, two downwardly extending sec-

tions 32, 33; the complete rod thus constituted is designated by the numeral 31 where hereinafter referred to as a whole. The section 32 has a diameter larger than that of either the section 33 or the section 31. Two shoulders are thus formed, the upper one of which engages the lower end of the sleeve 19 and, together with a disc 31^a secured to the top of the section 31, prevents relative longitudinal movement of the sleeve. The lower shoulder 32^a co-operates with a detent 34. This detent is pivotally mounted upon a shaft 35 (Figure 8) and has pivoted to it a bar 36, which, as shown in Figure 2, has a U-shaped slot 37 through which passes a pin 38 fast to the vise frame. By engaging the respective ends of the slot over the pin the bar can be locked in one or other of the two terminal positions shown respectively in Figures 1 and 2. In the position indicated in Figure 2, the detent 34 is in engagement with the shoulder 32^a, and the rod 31 thereby held against downward movement, whereas, in the second position indicated in Figures 1 and 8, the detent 34 is withdrawn and leaves the rod free.

The rod section 33 has a flattened portion 39 against the surface of which (see particularly Figures 8 and 12), a roller 40 is adapted to bear. This roller 40 is eccentrically mounted on a shaft 41 to which is fast a lever 42 carrying two abutment screws 43 and 44. The lever 42 is constrained to move clockwise, as viewed in Figure 12, by a spring 45. The screw 44 limits the said clockwise movement by contacting with an abutment surface formed on the vise frame. The second abutment screw 43 is engaged by the front end of the justification lever 46 during the latter's descent.

The justification lever 46, when at rest, is in a position somewhat higher than that in which it is shown in Figure 12, with the lever 42 to some extent depressed by it against the action of the spring 45. In consequence of the eccentricity of the roller 40 to the shaft 41, said roller, when the lever is depressed, will be pressed against the flat face 39 of the rod section 33 and thereby securely clamped and temporarily lock the rod in position. The supplemental downward movement of the justification lever 46 is effected for this purpose by an additional cam surface on the justification cam, and in Figure 12 the lever 46 is shown near the completion of its descent.

At the lower end of the rod section 33 is mounted a cross bar 47 to which are attached the upper ends of two springs 48, whose lower ends are connected to two arms or brackets 49 fast to the vise frame. The springs 48 constantly tend to pull downwardly the rod 31 and the parts associated therewith. In order to lock the rod against the action of the springs 48, a further detent 50 is provided, the form and action of which will be explained by reference to Figures 8, 11 and 12. The detent 50 is pivoted to swing in a horizontal plane about a fixed stud 51 on the vise frame; it is in the form of a hook-shaped flat plate and is adapted to engage edgewise with an annular recess 52 in the rod section 33, under the influence of a spring 53. At one end the detent 50 is provided with a downwardly extending arm 54 in a position to be engaged by the justification lever 46. When the latter is moved upwardly beyond the position in which it is shown in Figure 12, it will contact with the arm 54 and swing the detent 50 in the direction indicated by the arrow in Figure 11, out of engagement with the annular recess 52, thus releasing the rod 31.

which, provided the detent 34 is in the disengaged position shown in Figure 1, will be drawn down by the springs 48.

The raising of the rod 31 and its associated parts, and the extending or re-energizing of the springs 48, are effected by the lever 55, which raises the first elevator to its topmost position. This lever 55 is of known form and only a portion of its front end is represented in the drawings. As shown in Figure 15, said front end is pivotally connected to one end of a link 56, whose other end is connected to the first elevator 80 by a pin 57 and slot 58. A tension spring 59 interposed between the link 56 and the first elevator 80, normally holds the pin 57 against the upper end of the slot 58, and retains it in that position during the ascent of the first elevator. The first elevator cam is provided with a supplemental cam surface to give the lever 55 an upward movement in excess of that required to bring the elevator to its topmost position. During this excess movement, which is permitted by the pin and slot connection 57, 58, and the extension of the spring 59, the lever 55 contacts with the lower end 60 of the rod 31 and raises the latter against the action of the springs 48.

The rod section 32 is provided with a vertical rack 61 (Figures 1, 2 and 8), with which engages a pinion 62 on the shaft 35, said shaft being carried by a bracket 63 fast to the vise frame. The shaft 35 has fast on it a ratchet wheel 64 which serves, in co-operation with a pawl 65, for locking the shaft as hereinafter described. The locking pawl 65 is pivoted at 67 to a lever 68 loosely mounted on the shaft 35, and which lever has fixed to it a pin 66 adapted to bear against the outer edge of the detent 34. A spring 66^a, fastened at one end to a pin 66^b on the side face of the pawl 65 and at the opposite end to a pin 66^c on the adjacent side face of the lever 68, holds the pawl against the pin 66 and out of engagement with the ratchet 64, and a spring 69 acting on the lever 68 normally maintains the pin 66 in engagement with the detent 34. When the detent 34 is brought into the position in which it is shown in Figure 8, the lever 68 and pawl 65, through the pin 66, are moved as a unit against the action of the spring 69 to bring the lever and an extension 65^a on the pawl into the path of a collar 78 on the justification rod 77.

The metal pump of the machine is locked in the usual manner by the pump stop lever 75, which just before each casting operation, is actuated towards the right, as viewed in Figures 1 and 2, to release the pump. According to the constructional form of the invention now being dealt with, this release is effected through a lever 73 pivoted at 74 to the vise frame, by the connections next to be described. The lever 68 (see Figure 10) is provided with a pin 70, and upon the shaft 35 is loosely mounted a further arm 71 formed with a shoulder 72 against which the pin 70 is caused to bear when the lever 68 is turned in the direction indicated by the arrow in Figure 10, or counter-clockwise in Figure 8. The arm 71 (Figures 1, 2 and 8) is pivotally connected to the lower end of a vertically guided bar 72¹, whose upper end is pivoted to the lever 73, the free end of which, in known manner, bears against the pump stop lever 75. A spring 76 normally holds the lever 73 in its inactive position. Near the completion of the justification operation, when the pawl extension 65^a and the lever 68 are successively engaged by the collar 78 on the justification rod 77, the pawl is brought

into engagement with the ratchet 64 and the lever is then turned as above described and effects the release of the pump only when justification has been properly effected. Simultaneously with the release of the pump, the locking pawl 65, then in engagement with the ratchet wheel 64, will be rocked by the movement of the lever 68, and the said wheel, together with the toothed pinion 62, will be moved clockwise as viewed in Figure 8, so that, through the rack 61 and springs 10 48, the rod 31 will be depressed, and the jaws 2, 3, thereby tightened on to the composed matrix line located between them.

The longitudinal movement of the vertical rod 16 is effected by the locking detent 34 through 15 an arm 79 connected to the said detent.

The operation of the parts so far described is as follows:—When it is desired to operate the machine normally the bar 36 is moved to the position in which it is shown in Figure 2, so that 20 the detent 34 locks the rod 31 in its raised position. Consequently, although each operative movement of the justification lever 46 brings the detent 50, 54 out of engagement with the rod 31, said rod will remain stationary. Moreover, in the 25 inactive setting of the parts, the lever 13, through the rod 16, has been moved to the position shown in Figure 3, the pin 14 being thereby retracted, and the disc 17 is independently adjusted to the position indicated in Figure 3, out of engaging 30 relationship to the lever 11; hence the levers 10, 11, and the jaws 2, 3, are free to move independently in the usual manner.

When it is desired to bring the devices according to the invention into operation, the bar 36 35 is moved to the position represented in Figure 1, to withdraw the detent 34 out of engagement with the rod section 32, with the result that each time justification begins to take place, the detent 50 is released and the rod 31 permitted to 40 descend under the action of the springs 48. According to the angular adjustment of the sleeve 19, determined by the position of the crank handle 28, the disc 17 when descending will take with it either one or both of the pins 12, 14, and thus 45 move one or both of the vise jaws 2, 3, inwards to bring them into contact with each other or with the respective ends of the composed line between them.

During the downward movement of the rod 31, 50 i. e., when either or both of the jaws 2, 3, move inwardly, the shaft 35 will be turned idly by the engagement of the rack bar 61 with the toothed wheel 62. Shortly after the completion of said downward movement, however, the collar 78 on 55 the justification rod 77, contacts with the pawl 65 and immediately thereafter with the lever 68, so that its pin 70 will rock the lever 71 downwardly and the locking pawl 65, also carried by the lever 68, will act on the ratchet wheel 64. 60 The pump will thus be released through the lever 11, so as to permit the casting operation to take place, and downward pressure will be applied to the rod 31 through the toothed wheel 62 by the action of the pawl 65 on the ratchet wheel 64 65 to tighten the jaws on the line.

After casting, the first elevator in the well-known manner raises the composed line out of the vise to enable it to be transferred to the distributing mechanism. However, before the 70 line is removed from between the jaws, the justification lever 46 will have completed its downward movement, and brought the brake lever 42 into its active position to temporarily hold down the rod 31. This prevents the two jaws 2, 3, from 75

violently contacting with each other under the action of the springs 48, when the matrix line is removed from between them.

After the first elevator has reached its uppermost position, the first elevator lever 55, by its supplemental upward movement permitted by the spring 59, raises the rod 31, the brake lever 42 having in the meantime been released by an upward movement of the justification lever 46, until the detent 50 again enters the groove 52 of the rod section 33, the springs 48 being thus extended and the parts retained in the normal position preparatory to the initiation of the next cycle of operations. The device continues to operate at every operative cycle of the machine until the rod 31 is again locked and the pins 12 and 14 are again released by returning the bar 36 and the crank handle 38 to the position in which they are shown in Figure 2.

When casting alternately lines of full length, (i. e. lines not to be quadded or centred) and shorter lines to be centred or quadded, it is not necessary to throw the device out of action for alternate casts by shifting the bar 36. Under those conditions, however, it may happen that full-length lines or lines to be quadded, which contain spacebands, may be so tightly clamped by the jaws, that the justifier cannot actuate the spacebands to effect proper justification. In order to overcome this difficulty the mechanism illustrated in Figures 16 to 18 may be provided. According to the arrangement there shown, an additional ratchet wheel 81 is fixed to the shaft 35, and a pawl 82 adapted to engage therewith is pivoted to the inclined link 83 which, as ordinarily, serves to control the justification bar 84. The action of the pawl 82 on the ratchet wheel 81 is controlled by a cam-shaped shroud 85 rigidly attached to the machine frame, as by a bracket 86. The shroud 85 is formed so that the pawl 82 can engage the ratchet wheel 81 only when the link 83 reaches a certain position and so as to ensure that the ratchet wheel can be turned to a definite extent only. The pawl is disengaged from the ratchet wheel on further movement of the link 83 by an inclined surface on the shroud 85. If for constructional reasons the shroud 85 cannot limit sufficiently the rotation of the ratchet wheel 81 under the action of the pawl 82, there may be provided, as shown in Figure 18, a segmental slot in the hub of the wheel 81 and a pin on the shaft 35 extending into the slot, the arrangement being such that the ratchet wheel 81 will turn idly to the extent of the play permitted by the slot before taking the shaft 35 with it. According to this arrangement, shortly before the justification bar 84 comes into contact with the feet of the spacebands to effect the expansion of the latter, the pawl 82 will engage the ratchet wheel 81 and turn it together with the shaft 35, which is then not locked by the pawl 65, as such locking takes place, as previously explained, at the completion of justification. The shaft 35 when thus turned by the pawl 82, takes with it the toothed wheel 62 and the latter through the rack 61 raises the rod 31, thus moving the two jaws 2, 3, outwardly to slacken the line to the required extent.

While slackening of the line as just described for the purpose of permitting justification to take place, is necessary in the case of full-length lines, or lines to be quadded, it is desirable to provide means for preventing the outward line-slackening movement of the jaws in the case of lines which

are to be centred. Such means are illustrated in Figures 19, 20 and 21.

In this construction the pawl 82 has a roller 82^a, bearing on the cam-shaped shroud 85, which controls the actuation of the ratchet wheel 81, as in the arrangement before described.

For the angular adjustment of the sleeve 19 in this constructional form of apparatus, the handle 28, instead of being in the form of a crank as previously described, is in the form of a lever fast on a shaft 28^a to which is secured a lever 28^b, connected by a link 28^c (shown in dotted lines in Figure 20) to the rack bar 25.

The lever 28^b has a cam arm 107, arranged to engage a slide 108 constantly held in contact with the cam arm by a spring 109. The slide 108 has a downwardly directed arm 110 which is forked at its extremity to engage a stud 111 on a slide 112 movable laterally, in a fixed guide, towards and away from the pawl 82. When the cam arm 107 occupies the intermediate position in which it is shown in full lines in Figure 20, the slides 108, 112, will be in their rightmost positions as viewed in that figure, so that, through the roller 82^a, the pawl 82 (as shown in Figure 19) is held out of engagement with the ratchet wheel 81. On the other hand, in the extreme left and right positions of the hand lever 28, (the latter being indicated in dotted lines in Figure 20), the cam arm 107 permits the slide 108 to move leftward, under the action of the spring 109, the roller 82^a then engaging with the shroud 85 (see Figure 21) so that the slackening of the line is effected in the manner described above.

It will now be understood that when full-length lines only are required to be cast, the quadding and centring apparatus according to the invention can be thrown out of action, and that when casting alternately full length lines, or shorter lines to be centred or quadded, the apparatus may remain operatively connected. In the latter case, when dealing with full length lines, the before-described means for tightening the jaws on to the line would remain operative, although such tightening of the jaws is not actually required in the case of full lines because one of the jaws (usually the left-hand jaw) bears against a stop which is adjustable for the length of line required, and cannot yield, and therefore the line is properly tightened when the spacebands are raised for effecting justification. When the centring or quadding apparatus is operative, moreover, the tightening of the jaws to compact a full length matrix line may possibly result in the production of a centred or quadded line should the spacebands be insufficient to expand the line to the full length.

The present invention, therefore, includes means for preventing lines which are composed to a certain measure from becoming centred or quadded lines. When composing, the maximum slackness in the line which can be left to be filled out by justification is so calculated that it will approximately correspond to the justification capacity of the spacebands present in a normal line of the required length, for example, 1 em for short lines, 2 ems for lines of medium length, and 3 ems for long lines.

The arrangement provided according to the invention, therefore, is designed to be adjusted for one, two or three ems maximum slackness, and prevents the operation of the device for tightening the jaws after justification, when the amount of space to be filled out by justification does not exceed one, two or three ems as the case may be. If this amount is exceeded, then the line will be

automatically centred or quadded; but, if these amounts are not exceeded, the line will be cast as a full line, except in the case of the spacebands being too few to take up the amount allowed for 5 justification when the pump stop will become operative and the line will not be cast at all. If, with the application of the device according to the present invention, it is desired to obtain a centred or quadded line, although there is less than 10 the pre-selected amount of one, two or three ems available in the line, the remaining portion of the line must be filled out with space matrices or quads.

According to this feature of the invention, the 15 ratchet wheel 64 above described is provided with teeth on only part of its periphery, as shown in Figures 24 to 26. The vise frame 1 has rigidly mounted thereon a pivot 88 on which is carried a three-armed lever 90 which, by means of a handle 20 89 may be adjusted to four different positions. When the lever 90 is in the position in which it is shown in dot-and-dash lines in Figure 22, the device is inoperative, while the positions indicated at I, II, III, correspond with the respective lengths 25 of line required to be dealt with by the machine. The position I, in which the lever 90 is represented in full lines in Figure 22, is that intended for short lines, position II for medium length lines, and position III for long lines.

The pawl 65 is, in this constructional form, carried by an arm 91 on a pivot 92 (see particularly Figure 27). The arm 91 carries a pin 93 against which is adapted to bear a projection 94 fast to the lower arm of the three-armed lever 90. The 30 position (I, II or III) occupied by the three-armed lever 90 therefore determines the level at which the projection 94 will hold the pin 93 and arm 91, and the position of the pawl 65 relatively to the toothed portion of the ratchet wheel 64. The 35 operative positions of the pawl 65 corresponding to the positions I, II and III of the lever 90 are shown respectively in Figures 24, 25 and 26. The pawl 65 normally bears on a toothless part of the ratchet wheel 64. When the lever 90 is in the 40 position I, the distance of the pawl 65 from the nearest ratchet tooth will be comparatively small, as indicated in Figure 24, but for the positions II and III (Figures 25 and 26) it will be progressively greater.

This mechanism operates as follows:—When short lines are to be composed, the lever 90 is adjusted to the position I. The operator when he intends to cast full lines (not quadded or centred) must be careful that the line, as composed, is not 45 more than one em short of the desired full-line length. After the composed line is sent away with an allowance for justification up to one em, and is justified, the rod 31 will first be released through the justification lever as above described, 50 and the vise jaws will tend to move inwards under the action of the springs 48.

If the space left in the line is at the most one em, the jaws and the rod 31 will make only a small movement and the consequent clockwise 55 rotation of the ratchet wheel 64, as viewed in Figure 24, will be so small that no tooth thereof will be brought within range of the pawl 65, so that justification can proceed in the ordinary manner, the left-hand jaw bearing against its stop, as ordinarily, and a full line will result. The pawl 65, under these conditions, remains inoperative.

Corresponding action will take place when, for medium or long lines, the lever 90 is adjusted to the position II or III, the extent of the downward 60 movement of the rod 31 and of the clockwise ro-

tation of the ratchet wheel 64 with the detent 65 still on the toothless portion being correspondingly greater, so that two or three ems may remain to be taken up by justification of the line without any tooth of the wheel 64 being engaged by the pawl 65.

If the line, when the lever 90 is adjusted to the position I, is more than one em short, or if, when the lever is adjusted to the position II or III the line is more than two ems or three ems short, the 10 rod 31 will descend far enough to enable the pawl 65 to operatively engage the ratchet wheel 64, and consequently, at the end of the justification operation, the said wheel will be turned by the pawl 65, the rod 31 will be pulled further down- 15 wardly and the vise jaws will be pressed tightly against the line. This will result in a centred or quadded line being cast. When the lever 90 is adjusted to the "out" position, that is, the position in which it is represented in dot-and-dash 20 lines in Figure 22, the pawl 65 will be brought entirely out of engaging relationship with the ratchet wheel 64.

The actuation of the pawl 65 is effected by the justification lever 46, or a collar on the justification rod 71, coming into contact with the lower hook-shaped end 95 of said pawl and turning the latter together with the arm 91. During the said movement, the pin 93 will engage the free arm of a two-armed lever 96 pivoted at 97 30 to the vise frame and whose second arm, through a link 98, is connected to a bell-crank lever 99, which is pivotally connected to the lower end of a vertically movable rod 100, as shown in Figure 22. This rod 100 serves to operate the pump stop, 35 for which purpose it is connected to a vertical slide 101 which is adapted to co-operate with a horizontal sliding rod 102. The slide 101 is formed with two recesses one above the other. When the rod 102 is in engagement with one of these 40 recesses, the pump stop lever 75 is in its locking position. When the line is justified, the slide 101 will be pulled downwardly through the swinging movement of the arm 91, and when justification takes place in the ordinary manner, the sliding 45 rod 102 will reach the raised portion of the slide 101 and the pump will be free to operate. If a vise jaw, for any reason, becomes jammed, and cannot contact with the line, the spacebands will be completely expanded without filling out the 50 line. The pump should therefore be stopped. As the path travelled by the justification mechanism is in this case comparatively large the arm 91, and with it the mechanism actuating the slide 101, will be moved to a comparatively large extent, so that the sliding rod 102 will drop from the raised portion of the slide 101 into the notch 103, and the pump will consequently again be 55 locked.

It may happen that the pawl 65 engages very 60 closely and without any play, one of the teeth of the ratchet wheel 64 and that the said wheel cannot turn. The result of this is that, when justification takes place, the pawl 65 cannot move and the slide 101 will not be actuated, so that 65 the pump remains inactive and no cast is made. In order to overcome this difficulty, the rack engaging the wheel 62 is formed on a special sleeve 104, which, as shown in Figure 28, is capable of moving to a slight extent on and relatively to 70 the rod 31. Two springs 105, 106, hold the said sleeve in its intermediate position, these springs respectively bearing against two studs 105^a and 106^a. This arrangement renders it possible for the pawl 65 to move in the case previously de- 75

scribed, inasmuch as the said pawl will cause the sleeve 104 to be depressed by the wheel 62, against the action of the spring 105, when the shaft 35 begins to turn. Through this movement the slide 101 will be pulled downwardly and the pump will be released as previously described. The second spring 106 is intended to give the rack bar a certain flexibility in the other direction, namely, when the before-described pawl 82, through close engagement with the wheel 81 is unable to perform any movement. This happens when a line is so tight that movement of the jaws for slackening purposes is not practicable. The pawl 82 then becomes fast in the ratchet wheel 81 and breakage would occur when justification takes place. Such breakage, however, is prevented in this case by the spring 106 yielding for, although the rod 31 remains stationary, the ratchet wheel 81 will be moved under the action of the pawl 82.

Obviously the springs 105 and 106 must be of sufficient strength to prevent them from yielding when the pawl 65 or 82 operates ordinarily. These springs may be substituted by a spring engaging either the wheel 62 or the wheel 64 and a spring engaging the wheel 81.

In carrying out the invention, more especially when dealing with the alternate production of full lines and lines to be centered, the usual justification operating spring, by which the justification lever is moved, may not be sufficiently strong to effect satisfactory justification by reason of the additional pressure exerted on the matrix line by the centring device. The employment of a stronger spring is not practicable, because the pressure exerted by such a spring, through the justification lever, against the cam disc which operates it would result in undesirable wear of the cam and, further, the counter-pressure exerted upon the main shaft would at times be so great that it might affect the regular working of the machine.

It is, therefore, a feature of the present invention to provide counter-balancing means for the justification mechanism while leaving the justification spring at its normal strength. The preferred constructional form of this feature of the invention is illustrated diagrammatically in Figure 29, wherein 113 represents the main frame of the machine, 114 the main shaft which carries the cam 115 which controls the justification lever 46. The said lever is pivoted to the machine frame at 116 and carries a roller 117 bearing against the cam 115 under the influence of a spring 118 acting through a rod 119. The front end of the justification lever 46 is fork-shaped and embraces the respective rod 77 of the justification mechanism, which it operates through a collar or projection such as 78, in the well-known manner.

The counter-balancing means provided according to this constructional form of the device is in the form of an additional spring 120 adapted to urge the lower end of the rod 77 upwardly. This spring 120 is of such strength that at the instant at which the justification lever 46 comes into contact with the collar 78, the weight of the justification mechanism is practically completely counterbalanced. The spring 118, being thus relieved of the weight of the mechanism, will exert sufficient power on the spacebands, through the justification bar 84, to readily effect proper justification.

As there are two justification rods (77, 87), in parallel relationship, two springs 120 could be provided in place of a single spring of greater

strength. Moreover, counterweights or other means for exerting upward pressure on the rods could be substituted for springs.

Further, in order to reduce friction and thereby secure smoother operation of the apparatus, the jaws 2, 3, may be guided by rollers. A constructional form of such a roller guiding arrangement is illustrated in Figures 30 and 31 applied to the vise jaw 2. This jaw, like the jaw 3, is attached in the usual manner to a block 121 which is guided in the vise head. The block 121 may be provided with rollers 122 which run along the lower guiding surface of the vise head, or rollers 123 running along the upper guiding surfaces, or with rollers 122 and 123 as shown engaging both guiding surfaces.

It is to be understood that the particular constructional forms of the devices hereinbefore described and illustrated in the drawings are selected only as convenient examples of the means for carrying out the invention, and that modifications in the said forms may be made without departing from the invention. For example, instead of the rod 16 engaging with the lever 13, through the inclined slot 15, a lever connection 25 could be substituted, and the device could be operated by levers other than the justification lever. Any other suitably operated lever already on the machine might be employed, or a special lever controlled from the cam shaft.

Having described my invention, I declare that what I claim and desire to secure by Letters Patent is:—

1. In a typographical slug casting machine, the combination with a pair of jaws between which a composed line is clamped, a rod reciprocable to move said jaws towards and from each other and means for selectively coupling the line-clamping jaws with the rod, of a primary locking device for maintaining the rod in its normal position of rest and adapted to be thrown into and out of action at will and a secondary normally active locking device for the rod adapted to be released by a periodically operated member of the machine during each operative cycle.

2. In a typographical slug casting machine, the combination with a pair of jaws between which a composed line is clamped, a rod reciprocable to move said jaws towards and from each other and means for selectively coupling the line-clamping jaws with the rod, of a primary locking device for the rod adapted to be thrown into and out of action at will, and means adapted automatically to break the connection between one of the jaws and the rod when the primary locking device is rendered operative.

3. In a typographical slug casting machine, the combination with a pair of jaws between which a composed line is clamped, a rod reciprocable to move said jaws towards and from each other and means for selectively coupling the line-clamping jaws with the rod, comprising a disc angularly adjustable on the rod and two levers each having one arm connected to a respective jaw and a pin on its other arm adapted to engage beneath said disc, of a primary locking device for the rod adapted to be thrown into and out of action at will and means adapted automatically to move one of the pins out of engaging relationship with the disc when said primary locking device is rendered operative.

4. In a typographical slug casting machine the combination of a pair of jaws between which a composed line of matrices and spacebands is clamped, a justification lever by which the space-

bands are expanded to justify the line, a reciprocable rod spring-actuated to move the line-clamping jaws towards the line, means for selectively coupling the line-clamping jaws with the 5 rod, supplemental rod-actuating mechanism operated by the justification lever to tighten the jaws against the line after the jaws are closed thereon, and a normally active locking device for the rod adapted to be released by a periodically 10 operated member of the machine during each operative cycle.

5. In a typographical slug casting machine the combination of a pair of jaws between which a composed line of matrices and spacebands is 15 clamped, a justification lever by which the spacebands are expanded to justify the line, a reciprocable rod spring-actuated to move the line-clamping jaws towards the line, means for selectively coupling the line-clamping jaws with the 20 rod, supplemental rod-actuating mechanism operated by the justification lever to tighten the jaws against the line after the jaws are closed thereon, and a normally active locking device for the rod adapted to be released by the justification 25 lever during each operative cycle.

6. In a typographical slug casting machine, the combination of a pair of jaws between which a composed line of matrices and spacebands is clamped, a justification lever by which the spacebands are expanded to justify the line, a reciprocable rod spring-actuated to move the line-clamping jaws towards the line, means for selectively coupling the line-clamping jaws with the rod, supplemental rod-actuating mechanism 30 comprising a ratchet wheel and a pawl operated by the justification lever to tighten the jaws against the line after the jaws are closed thereon, a primary locking device for the rod adapted to be thrown into and out of action at will, and 35 means adapted to move the pawl of the supplemental rod-actuating mechanism into and out of engaging relationship to its ratchet wheel when said locking device is moved to inactive and active position respectively.

45 7. In a typographical slug casting machine, the combination of a pair of jaws between which a line is clamped, a rod reciprocable to close and open said jaws, means for selectively coupling the line-clamping jaws with the rod, a locking device 50 normally active to retain the rod in a normal position in which it holds the jaws apart, means adapted to release said locking device during each operative cycle of the machine to permit the jaw-closing movement of the rod, and means adapted 55 to return the rod to said normal position at the completion of each operative cycle.

8. In a typographical slug casting machine, the combination of a pair of jaws between which a line is clamped, a rod reciprocable to close and 60 open said jaws, means for selectively coupling the line-clamping jaws with the rod, a locking device normally active to retain the rod in a normal position in which it holds the jaws apart, means adapted to release said locking device during each 65 operative cycle of the machine to permit the jaw-closing movement of the rod, means adapted to return the rod to said normal position at the completion of each operative cycle, and a brake device rendered operative to lock the rod when the 70 composed line is removed from between the jaws after casting and prior to the return of the rod to normal position.

9. In a typographical slug casting machine, the combination of a pair of jaws between which a 75 line of matrices and spacebands is clamped, a

justification lever by which the spacebands are expanded to justify the line, a reciprocable rod spring-actuated to close the line-clamping jaws, means for selectively coupling said jaws with the rod, a locking device normally active to lock the rod in said normal position and adapted to be released by movement of the justification lever to permit the jaw-closing movement of the rod, a periodically operated lever adapted to return the rod to normal position after removal of the line 10 from between the jaws, and a brake device actuated by the justification lever to temporarily lock the rod against jaw-closing movement during the period between the said removal of the line and the return of the rod to normal position. 15

10. A combination according to claim 9, wherein in the brake device comprises a shaft, a roller eccentrically mounted on said shaft and adapted to engage the reciprocable rod, a spring constantly tending to prevent such engagement and 20 an arm fast on said shaft adapted to be engaged by the justification lever to turn the shaft against the action of said spring.

11. In a typographical slug casting machine, the combination of a pair of jaws between which a composed line of matrices and spacebands is 25 clamped, a justification lever by which the spacebands are expanded to justify the line, a pump stop lever operable to release the pump when a line is properly justified, a reciprocable rod 30 spring-actuated to move the line-clamping jaws towards the line, means for selectively coupling the line-clamping jaws with the rod, supplemental rod-actuating mechanism operated by the justification lever to tighten the jaws against 35 the line after the jaws are closed thereon, and connections from said supplemental rod-actuating mechanism to the pump stop lever adapted to release the pump simultaneously with the actuation of said supplemental rod-actuating mech- 40 anism.

12. In a typographical slug casting machine, the combination of a pair of jaws between which a composed line of matrices and spacebands is 45 clamped, a justification lever by which the spacebands are expanded to justify the line, a pump stop lever operable to release the pump when a line is properly justified, a reciprocable rod 50 spring-actuated to move the line-clamping jaws towards the line, means for selectively coupling the line-clamping jaws with the rod, supplemental rod-actuating mechanism operated by the justification lever to tighten the jaws against 55 the line after the jaws are closed thereon, connections from said supplemental rod-actuating mechanism to the pump stop lever adapted to release the pump simultaneously with the actuation of said supplemental rod-actuating mech- 60 anism, a primary locking device for the rod adapted to be thrown into and out of action at will and a secondary normally active locking device for the rod adapted to be released by the justification lever during each operative cycle.

13. In a typographical slug casting machine, the combination of a pair of line-clamping jaws, a rod reciprocable to close the jaws onto a composed line of matrices and spacebands located between the jaws and to open the jaws, means for selectively coupling the line-clamping jaws with the rod, a normally active locking device for the rod adapted to be released by a periodically operated member of the machine during each operative cycle, means adapted to justify a line held between the jaws, and means actuated by 70 75

- the justification means adapted to spread the line-clamping jaws slightly apart immediately before justification.
14. In a typographical slug casting machine, the combination of a pair of line-clamping jaws, a rod reciprocable to close the jaws onto a composed line of matrices and spacebands located between the jaws and to open the jaws, means adjustable for selectively coupling the jaws to the rod for quadding or for centring a composed line, a normally active locking device for the rod adapted to be released by a periodically operated member of the machine during each operative cycle, means adapted to justify a line held between the jaws, means actuated by the justification means adapted to spread the line-clamping jaws slightly apart immediately before justification, and means adapted automatically to render said jaw-spreading means inoperative simultaneously with the setting of the rod-and-jaw coupling means for centring.
15. In a typographical slug casting machine, the combination of a pair of line-clamping jaws, a rod reciprocable to close the jaws onto a composed line of matrices and spacebands located between the jaws and to open the jaws, a member adjustable to selectively couple the jaws to the rod for quadding or for centring a composed line, a normally active locking device for the rod adapted to be released by a periodically operated member of the machine during each operative cycle, means adapted to justify a line held between the jaws, ratchet and pawl mechanism actuated by the justification means to spread the line-clamping jaws slightly apart immediately before justification, a slide adjustable to hold the pawl of said mechanism out of engagement with the ratchet, and connections between the adjustable rod-and-jaw coupling member and said slide adapted to move the latter to active position when adjusting said member for centring.
16. In a typographical slug casting machine, the combination of a pair of jaws between which a composed line of matrices and spacebands is clamped, a justification lever by which the spacebands are expanded to justify the line, a reciprocable rod spring-actuated to move the line-clamping jaws towards the line, means for selectively coupling the line-clamping jaws with the rod for quadding or centring a composed line, supplemental rod-actuating mechanism operated by the justification lever to tighten the jaws against the line after the jaws are closed thereon, means adapted to render the supplemental rod-actuating mechanism inoperative during the production of full lines when the device is set for quadding or centring, and a normally active locking device for the rod adapted to be released by a periodically operated member of the machine during each operative cycle.
17. In a typographical slug casting machine, the combination of a pair of jaws between which a composed line of matrices and spacebands is clamped, a justification lever by which the spacebands are expanded to justify the line, a reciprocable rod spring-actuated to move the line-clamping jaws towards the line, means for selectively coupling the line-clamping jaws with the rod, supplemental rod-actuating mechanism operated by the justification lever to tighten the jaws against the line after the jaws are closed thereon, said mechanism comprising a pawl and ratchet wheel toothed over only a part of its periphery, and means adapted to adjust the pawl to a position in which when actuated it will move idly over the untoothed part of the ratchet wheel.
18. In a typographical slug casting machine, the combination of a pair of jaws between which a composed line of matrices and spacebands is clamped, a justification lever by which the spacebands are expanded to justify the line, a reciprocable rod spring-actuated to move the line-clamping jaws towards the line, means for selectively coupling the line-clamping jaws with the rod, supplemental rod-actuating mechanism operated by the justification lever to tighten the jaws against the line after the jaws are closed thereon, said mechanism comprising a pawl and ratchet wheel toothed over only a part of its periphery, and means adapted to adjust the pawl to respectively different positions to ensure its engagement with the ratchet wheel teeth in different positions to accord with differing lengths of line to be produced.
19. In a typographical slug casting machine, the combination of a pair of jaws between which a composed line of matrices and spacebands is clamped, a justification lever by which the spacebands are expanded to justify the line, a reciprocable rod spring-actuated to move the line-clamping jaws towards the line, means for selectively coupling the line-clamping jaws with the rod, supplemental rod-actuating mechanism operated by the justification lever to tighten the jaws against the line after the jaws are closed thereon, said mechanism comprising a ratchet wheel, an arm adapted to rock about the axis of the ratchet wheel and a pawl pivoted to said arm, and an independently pivoted lever bearing against and adjustable to vary the angular position of said arm relatively to the ratchet wheel to ensure the engagement of the pawl with the ratchet wheel teeth in different positions to accord with differing lengths of line to be produced.
20. In a typographical slug casting machine, the combination of a pair of jaws between which a composed line of matrices and spacebands is clamped, a justification lever by which the spacebands are expanded to justify the line, a pump stop lever operable to release the pump when a line is properly justified, a reciprocable rod spring-actuated to move the line-clamping jaws towards the line, means for selectively coupling the line-clamping jaws with the rod, supplemental rod-actuating mechanism operated by the justification lever to tighten the jaws against the line after the jaws are closed thereon, said mechanism comprising a ratchet wheel, an arm adapted to rock about the axis of the ratchet wheel and a pawl pivoted to said arm, and an independently pivoted lever bearing against and adjustable to vary the angular position of said arm, and connections from said pawl carrying arm to the pump stop lever adapted to release the pump when the arm is moved to tighten the jaws on a properly justified line and to lock the pump by its excess movement when tightening the jaws on a slack line.
21. In a typographical slug casting machine, the combination of a pair of jaws between which a composed line of matrices and spacebands is clamped, a justification lever by which the spacebands are expanded to justify the line, a pump stop lever operable to release the pump when a line is properly justified, a reciprocable rod spring-actuated to move the line-clamping jaws towards the line, means for selectively coupling the line-clamping jaws with the rod, supplemental rod-actuating mechanism operated by the justification lever to tighten the jaws against the line after the jaws are closed thereon, said mechanism comprising a ratchet wheel toothed over only a part of its periphery, and means adapted to adjust the pawl to a position in which when actuated it will move idly over the untoothed part of the ratchet wheel.

- the line, means for selectively coupling the line-clamping jaws with the rod, supplemental rod-actuating mechanism operated by the justification lever to tighten the jaws against the line after the 5 jaws are closed thereon, and connections from said supplemental rod-actuating mechanism to the pump stop lever adapted to release the pump simultaneously with the actuation of said supplemental rod-actuating mechanism, said connections including a yielding member permitting the rod-actuating mechanism to move for the purpose of releasing the pump when the jaw-control rod is held stationary by a properly justified line.
22. In a typographical slug casting machine, 15 the combination of a pair of jaws between which a composed line of matrices and spacebands is clamped, a justification lever by which the spacebands are expanded to justify the line, a pump stop lever operable to release the pump when a line is properly justified, a reciprocable rod spring-actuated to move the line-clamping jaws towards the line, means for selectively coupling the line-clamping jaws with the rod, supplemental rod-actuating mechanism operated by the justification lever to tighten the jaws against the line after the jaws are closed thereon, said mechanism comprising a ratchet wheel, an arm adapted to rock about the axis of the ratchet wheel and a pawl pivoted to said arm, and an independently pivoted lever bearing against and adjustable to vary the angular position of said arm, connections from said pawl carrying arm to the pump stop lever adapted to release the pump when the arm is moved to tighten the jaws on a properly 30 justified line, and a yielding connection between the supplemental rod-actuating mechanism and the rod, permitting the pawl-carrying arm to move when actuated to close the jaws against a tightly justified line.
- 40 23. A combination according to claim 13, characterized by a yielding connection between the jaw controlling rod and the jaw-spreading means to prevent damage when the latter is actuated against a full line.
- 45 24. In a typographical slug casting machine, the combination with a pair of jaws between which a composed line is clamped, guides along which said jaws are movable, roller bearings for the jaws within said guides, a rod reciprocable to move the jaws along the guides towards and from each other, and means for selectively coupling the jaws with the rod.
- 55 25. In a typographical slug casting machine, the combination with a pair of jaws between which a composed line of matrices and spacebands is clamped, a spring-loaded justification lever by which the line is justified, justification devices actuated by said lever to expand the spacebands, a rod reciprocable to move said jaws towards and from each other, means for selectively coupling the jaws with the rod, means constantly tending to actuate the rod to move the jaws towards each other, a locking device normally acting to prevent such movement, means adapted to release said locking device prior to justification during each operative cycle and means adapted to counterbalance the weight of the justification devices during justification.
- 60 26. In a typographical slug casting machine, the combination of a pair of line clamping jaws, light pressure means acting constantly to move the jaws toward one another, means for selectively coupling the jaws with the jaw moving means, a locking device normally active to retain the jaws 70 in their open line receiving position, means adapt-

ed to release said locking device during each operative cycle of the machine to permit the closing of the jaws against a line of matrices, and means for preventing the further closing of the jaws when the line is removed after casting.

5 27. In a typographical slug casting machine, the combination of a pair of line clamping jaws, light pressure means acting constantly to move the jaws toward one another, means for selectively coupling the jaws with the jaw moving means, a locking device normally active to retain the jaws in their open line receiving position, means adapted to release said locking device during each operative cycle of the machine to permit the closing of the jaws against a line of matrices, 10 means for preventing the further closing of the jaws when the line is removed after casting, and means for returning the jaws to line receiving position at the completion of each operative cycle.

15 28. In a typographical slug casting machine, the combination of a pair of line clamping jaws, light pressure means acting constantly to close the jaws against a line of matrices and spacebands positioned between them, justifying means for expanding the spacebands to justify the line, 20 means for selectively coupling the jaws with the jaw closing means, a locking device normally active to retain the jaws in their open line receiving position, said locking device being released by the action of the justifying means during 25 each operative cycle of the machine to permit the closing of the jaws, and means for preventing the further closing of the jaws when the line is removed after casting.

30 29. In a typographical slug casting machine, the combination of a pair of line clamping jaws, light pressure means acting constantly to close the jaws against a line of matrices and spacebands positioned between them, justifying means for expanding the spacebands to justify the line, 35 40 means for selectively coupling the jaws with the jaw closing means, a locking device normally active to retain the jaws in their open line receiving position, said locking device being released by the action of the justifying means during 45 each operative cycle of the machine to permit the closing of the jaws, means controlled by the justifying means for preventing the further closing of the jaws when the line is removed after casting, and means for returning the jaws 50 to line receiving position at the completion of each operative cycle.

30 30. In a typographical slug casting machine, the combination of a pair of jaws between which a composed line of matrices and spacebands is 55 clamped, a justification lever by which the spacebands are expanded to justify the line, a pump stop lever operable to release the pump when a line is properly justified, means for moving the line clamping jaws towards the line, means for 60 selectively coupling the jaws to said jaw moving means, supplemental means operated by the justification lever to tighten the jaws against the line after the jaws are closed thereon, and connections from said supplemental means to the 65 pump stop lever adapted to release the pump simultaneously with the actuation of said supplemental means.

35 31. In a typographical slug casting machine, the combination of a pair of line clamping jaws, 70 light pressure means for closing said jaws onto a composed line of matrices and spacebands located between the jaws and to open the jaws, means for selectively coupling the line clamping jaws with the jaw closing means, a normally 75

- active locking device to retain the jaws in their open line receiving position adapted to be released by a periodically operated member of the machine during each operative cycle, means 5 adapted to justify a line held between the jaws, and means actuated by the justification means adapted to spread the line clamping jaws slightly apart immediately before justification.
32. In a typographical slug casting machine, 10 the combination of a pair of line clamping jaws, light pressure means for closing the jaws onto a composed line of matrices and spacebands located between the jaws and to open the jaws, means adjustable for selectively coupling the 15 jaws to the jaw closing means for quadding or centering a composed line, a normally active locking device for retaining the jaws in their open line receiving position adapted to be released by a periodically operated member of the 20 machine during each operative cycle, means adapted to justify a line held between the jaws, means actuated by the justification means adapted to spread the line clamping jaws slightly apart immediately before justification, and means 25 adapted automatically to render said jaw spreading means inoperative simultaneously with the setting of the adjustable jaw coupling means for centering.
33. In a typographical slug casting machine, 30 the combination of a pair of line clamping jaws, light pressure means for closing the jaws onto a composed line of matrices and spacebands located between the jaws and to open the jaws, means adjustable to selectively couple the jaws to the 35 jaw closing means for quadding or centering a composed line, a normally active locking device for the jaw closing means adapted to be released by a periodically operated member of the machine during each operative cycle, means adapted 40 to justify a line held between the jaws, mechanism actuated by the justification means to spread the line clamping jaws slightly apart immediately before justification, a movable member for rendering said mechanism operative or inoperative, 45 and connections between the adjustable jaw coupling means and said member adapted to actuate the latter to render said jaw spreading mechanism inoperative when adjusting said jaw coupling means for centering.
- 50 34. In a typographical slug casting machine, the combination of a pair of jaws between which a composed line of matrices and spacebands is clamped, a justification lever by which the spacebands are expanded to justify the line, light 55 spring pressure means for moving the line clamping jaws towards the line, means for selectively coupling the line clamping jaws with the jaw moving means for quadding or centering a composed line, supplemental jaw moving mechanism 60 operated by the justification lever to tighten the jaws against the line after the jaws are closed thereon, means adapted to render the supplemental jaw closing mechanism inoperative during the production of full lines when the device is set for quadding or centering, and a normally active locking device for retaining the jaws in their open line receiving position adapted to be released by a periodically operated member of the machine during each operative cycle.
- 65 35. In a typographical slug casting machine, the combination of a pair of jaws between which a composed line of matrices and spacebands is clamped, a justification lever by which the spacebands are expanded to justify the line, light 70 spring actuated means for moving the line clamp- 75 ing jaws towards the line, means for selectively coupling the line clamping jaws with said jaw moving means, supplemental jaw closing mechanism operated by the justification lever to tighten the jaws against the line after they are closed thereon, said mechanism comprising a pawl and ratchet wheel toothed over only a part of its periphery, and means adapted to adjust the pawl to a position in which when actuated it will move idly over the untoothed part of the ratchet wheel. 10
36. In a slug casting machine, the combination of a pair of line clamping jaws, means for moving one of the jaws into contact with a composed line of matrices and expansible spacebands, means for expanding the spacebands to justify the line, 15 and means actuated by the justifying means for moving said jaw outwardly a limited distance to permit the line to be expanded.
37. In a slug casting machine, the combination of a pair of line clamping jaws, one movable 20 toward the other for quadding, means for effecting such quadding movement of the jaw to bring it into contact with a composed line of matrices and expansible spacebands, means for expanding the spacebands to justify the line, and means actuated by the justifying means for moving said jaw outwardly a limited distance to permit the line to be expanded.
38. In a slug casting machine, the combination of a pair of line clamping jaws movable equidistantly toward each other for centering, means for effecting such centering movement of the jaws to bring them into contact with a composed line of matrices and expansible spacebands, means for expanding the spacebands to justify the line, 35 and means actuated by the justifying means for moving said jaws outwardly equal limited distances to permit the line to be expanded.
39. A combination as in claim 36, including means actuated by the justifying means to clamp 40 the jaw tightly against the justified line.
40. A combination as in claim 36, wherein the justifying means acts successively to actuate means for moving the jaw outwardly, to expand the line a corresponding extent, and to actuate 45 means for clamping the jaw tightly against the expanded line for casting.
41. A combination as in claim 36, wherein the justifying means acts successively to actuate means for moving the jaw outwardly, to expand 50 the line a corresponding extent, to actuate means for clamping the jaw tightly against the expanded line for casting, and to operate means for preventing the further inward movement of the jaw when the line is removed after casting. 55
42. A combination as in claim 36, wherein the jaw closing means comprises light pressure means acting constantly to move the jaws toward each other and including a normally active locking device for maintaining the jaws in their normal line receiving position and adapted to be released by a periodically operated member of the machine during each operative cycle. 60
43. In a slug casting machine, the combination of a pair of line clamping jaws, means for selectively closing one or both of the jaws upon a composed line of matrices and expansible spacebands for quadding or centering, justifying means for expanding the spacebands to justify the line, 65 means for conditioning the machine for quadding or centering, means controlled by the justifying means to effect an outward movement of the jaws from line closing position to spread the jaws for 70 expansion of the line, and means for rendering 75

said jaw spreading means inoperative when the machine is conditioned for centering.

44. In a slug casting machine, the combination of a pair of line clamping jaws, means for moving one of said jaws inwardly from its line receiving position into contact with a composed line of matrices and expandable spacebands for quadding, means for expanding the spacebands to justify the line, and means controlled by the justifying means and dependent upon the extent

of inward movement of the jaw to permit quadding or to return the jaw to normal line receiving position to allow the line to be expanded to full length.

45. A combination as in claim 44, including means actuated by the justifying means to prevent casting in the event of the failure of the line to be expanded to full length. 5

CHRISTIAN AUGUSTUS ALBRECHT. 10
